HYDROCARBON CONVERSION

Louis P. Evans, Woodbury, N.J., assignor to Socony Mobil Oil Company, Inc., a corporation of New York

Application October 13, 1954, Serial No. 461,965

2 Claims. (Cl. 214—152)

This invention relates to hydrocarbon conversion systems and more particularly to the maintenance in such systems of seals between zones of different pressures.

In the cracking of hydrocarbons to produce an increased yield of hydrocarbons boiling in the gasoline range it is customary to employ a continuously moving bed of granular catalyst material. Succeeding portions of this material flow through a reactor in which the conversion of the hydrocarbon material takes place. During this reaction the contact material becomes contaminated and provision is therefore made to deliver the moving bed to a regenerator wherein the contaminants are burned off. Succeeding portions of the regenerated contact material are then returned to the reaction or conversion zone.

It is desirable that the hydrocarbon conversion take place under pressure and that the regeneration of the contact material take place at atmospheric pressure. Accordingly the problem is presented of continuously feeding contact material into a regeneration zone while maintaining a positive pressure above atmospheric within that zone. One way to effect the seal is to use valves. These are, however, discontinuous in operation, expensive to install and maintain, and damaging to the contact material. Accordingly, resort has been had to feed legs long enough to maintain a head of contact material sufficient to keep the desired pressure level within the reactor. Since there is sometimes a considerable variation in the pressure within the reactor a valve has been retained for use under emergency conditions. While this arrangement involves only emergency use of a valve, it has been found that the valve is inclined to fail at the very time it is most needed.

It is, therefore, an object of the present invention to overcome the disadvantages of the prior art and to provide for the safe sealing of high pressures without the use of a mechanical safety valve by providing a pressure release and alarm system.

It is contemplated according to the present invention to prevent, by an automatic pressure adjustment, stoppage or reversal of contact material flow in a feed leg to a reactor when the pressure in the reactor temporarily exceeds the head of contact material.

Other objects and advantages of this invention will be apparent upon consideration of the following detailed description of a preferred embodiment thereof in conjunction with the annexed drawings, the single figure of which shows a portion of a moving bed contact material system with the present invention in operative position.

Referring now to the drawing in greater detail, it can be seen that the illustrated part of the system comprises an upper feed hopper 10, a seal leg 11, a lower feed hopper or intermediate pressure pot 12, a short feed leg 13, and a reactor 14. The moving bed of catalyst material enters the illustrated part of the system through a conduit 15 which is fed by a contact material elevator or the like. The contact material flows into the feed hopper 10, where the moving bed is established. The moving bed of material gravitates through the seal leg

2

11 and through the top 16 of the pressure pot 12. If there discharges into the pressure pot 12, from which it gravitates through the short leg 13 into the top of the reactor 14. A line 17 delivers a seal gas such as steam or flue gas to the top of the reactor 14.

In accordance with conventional practice, the contact material is discharged from the elevator through the conduit 15 into the feed hopper 10 at substantially atmospheric pressure. The catalyst gravitates as a compact mass through the elongated feed leg 11 into the top of the reactor 14, the reactor pressure being about 10 pounds per square inch gauge. In normal operation this feeding is continuous. A seal gas, such as steam or flue gas, is introduced through the conduit 17 into the top section of the reactor 14 at a pressure just slightly higher than the reactor pressure, such as, for example, 10½ to 10½ pounds, thereby producing a slight flow of gas upwardly through the seal leg to prevent reaction materials from flowing up through the seal leg. Thus, the moving bed of granular contact material extending from the feed hopper 10 to the reactor 14 itself constitutes the seal which prevents loss of pressure from the vessel 14. The height of the column of contact material above the reactor 14 is chosen in such a way that the weight per unit area of the bottom of the column of contact material is greater than the pressure per unit area existing within the reactor. Under these conditions gravity flow of the granular contact material continues and the reactor is maintained sealed.

Occasionally, because of processing difficulties, the pressure within the reactor 14 exceeds the design pressure for the system. It used to be customary to provide a cut-off valve near the bottom of the seal leg such as the leg 11. This was an emergency valve and it was intended to isolate the seal leg from the reactor if the reactor pressure got above a safe value. The valve did not operate very often and when called upon to operate failed on enough occasions to render its elimination desirable. According to this invention a valveless feeder technique is provided to provide a measure of safety in the event that the reactor pressure gets too high. The pressure pot 12 is a part of the apparatus introduced to eliminate a valve near the bottom of the leg 11. Also constituting a part of this system is a conduit 18 leading from the top of the pressure pot 12 to a differential pressure measurement device 19. Another conduit 20 leads from the device 19 to the top of the seal leg 11. The differential pressure device 19 is not described in detail but it is understood that it may be of any of the well known devices available on the market today which are capable of closing an electric circuit in response to a pressure difference in excess of a predetermined value. The electric circuit may be connected to an alarm device and/or to a valve such as valve 21 which is connected through a conduit 22 to the gas zone at the top of the pot 12. A major portion of the seal leg 11 is above the seal pot 12 and discharges catalyst into the seal pot. Normally, the vent valve 21 is closed so that the catalyst feeds uniformly into the reactor. When the pressure in the reactor rises above a safe level, the valve 21 opens, permitting seal gas to escape from the region in the seal pot 12 above the bed of catalyst. This provides a pressure differential across the short leg 13 more than sufficient to elevate the catalyst in the leg. However, the vessel 12 has a substantially greater cross-section than the seal leg 13 so that the gas flowing upwardly through the catalyst is dispersed in the mass and the upward velocity of the gas is reduced below what is termed the bed disrupting velocity. The bed disrupting velocity is that upward velocity at which the catalyst just starts to be disturbed or go into boiling movement with increase in gas velocity.

The catalyst mass in hopper 12 has a cross-section large enough to reduce the gas velocity below the bed disrupting velocity at some level below the surface of the catalyst mass. There is, therefore, provided above this critical level a sufficient depth of catalyst to provide a downward force component which will keep the contact material in the conduit 13 in compact and static condition. This, of course, prevents the transfer of catalyst through the seal leg 11 and the catalyst level will commence to rise in the feed hopper 10 and the unit must be shut down or the difficulty corrected promptly in order to prevent catalyst from flowing back from conduit 15 into the rising elevator or pneumatic lift. It is seen that during these emergency conditions no catalyst will flow through the seal leg and through the conduit 13, but catalyst may be drawn downwardly through the reactor and away from the lower end of pipe 13, leaving the catalyst suspended in the legs 11 and 13 until such time as normal conditions are restored.

This entire operation is automatic. The dual pressure indicator 19 measures the pressure differential across the seal leg during normal operation and when this pressure differential exceeds a safe upper limit it actuates the valve 21, thereby positively preventing the flow of catalyst through the seal leg system until the difficulties are corrected. Since the dual pressure indicator is also connected to an alarm, the operator is warned to either correct the difficulty and resume normal operation or shut the unit down promptly to prevent operational difficulties.

The leg 13 does not have to be very long but at least some length of leg must be provided. It should be at least 2½ times the diameter in length, and preferably as much as 5 times the diameter in length.

What is claimed is:

1. In a process in which a granular contact material is transferred as a compact gravitating column through reaction and regeneration zones, wherein the reaction zone pressure is substantially greater than the regeneration zone pressure and wherein the granular material is introduced into the higher pressure reaction zone as a

compact gravitating column of restricted cross-section and elongated height located directly above the reaction zone from a storage zone atop the column maintained at substantially the same pressure as the regeneration zone, the method of providing a safety seal to prevent the escape of reactants from the reaction zone and loss of the compact gravitating seal column in the event of the occurrence of abnormally high pressure in the reaction zone comprising the steps of: introducing a seal gas into the elongated column at the lower end thereof at a pressure not substantially greater than the reaction zone pressure, expanding the column laterally in the lower portion of a safety zone located intermediate the top and bottom of the column, so that as the contact material gravitates in compact form through the safety zone it covers a cross-sectional area substantially greater than the cross-section of the column above and below the safety zone, withdrawing gas from the upper portion of the safety zone in response to a rise of pressure in the reaction zone above a determined safe operating pressure at a flow rate sufficient to substantially reduce the upward gas velocity of gas flowing upwardly through the column in the safety zone to a gas velocity below the bed disruption velocity, the cross-section and depth of the column in the safety zone being sufficient to maintain the column in compact static condition whereby the escape of reactants from the reaction zone is prevented and the compact column is retained intact until normal operating conditions are restored in the reaction zone.

2. Claim 1 further characterized in that a warning alarm is automatically sounded simultaneously with the stoppage of flow of the column of contact material.
